CLAIM

I claim the ornamental design for the mount for an adjustable retail merchandise hook, as shown and described.

(22) Filed: **Sep. 18, 2013**

DESCRIPTION

(51) **LOC (10) Cl.** **08-05**

FIG. 1 is a perspective view of the mount for an adjustable retail merchandise hook in a first operational environment; FIG. 2 is another perspective view thereof in the operational environment shown in FIG. 1;

(52) **U.S. Cl.**

FIG. 3 is another perspective view thereof in a second operational environment;

USPC **D8/363**

FIG. 4 is another perspective view thereof in the second operational environment shown in FIG. 3;

(58) **Field of Classification Search**

FIG. 5 is another perspective view thereof;

USPC D8/383, 374, 300, 303, 313, 314, 394,

FIG. 6 is another perspective view thereof;

D8/396, 380, 373, 395, 363, 381, 44, 19,

FIG. 7 is a top view thereof;

D8/352, 370, 308, 372, 376; D13/133;

FIG. 8 is a side view thereof;

D19/1; D22/108; D26/87; D9/686,

FIG. 9 is a front view thereof;

D9/687; D23/238; D6/300

FIG. 10 is another side view thereof, showing the side opposite that shown in FIG. 7;

CPC ... A47F 5/0006; A47F 5/0823; A47F 5/0861;

FIG. 11 is a back view thereof; and,

A47F 7/148; G09F 7/18

FIG. 12 is a bottom view thereof.

See application file for complete search history.

The dashed lines shown in the corresponding figures are for purposes of illustrating the environment of the claimed design and form no part of the claimed design.
